Primary Examiner—Raphael Barkai*Attorney, Agent, or Firm*—Finnegan, Henderson, Farabow, Garrett & Dunner, L.L.P.[57] **CLAIM**

The ornamental design for a chassis for in-line roller skate, as shown and described.

DESCRIPTION

FIG. 1 is a perspective view of the chassis for in-line roller skate according to this design;

FIG. 2 is a top plan view of the chassis shown in FIG. 1; FIG. 3 is a side elevational view of the chassis shown in FIG. 1;

FIG. 4 is a bottom plan view of the chassis shown in FIG. 1;

FIG. 5 is a right end elevational view of the chassis shown in FIG. 1;

FIG. 6 is a left end elevational view of the chassis shown in FIG. 1;

FIG. 7 is a side elevational view of the chassis for in-line roller skate according to this design shown attached to a skate that is depicted in phantom lines; and,

The broken lines in FIG. 7 are for illustrative purposes only and form no part of the claimed design.
